2,568,893

EXTENSIBLE MEMBER FOR ADJUSTABLY ATTACHING A LIGHT DIFFUSER TO A LIGHTING

Josef Krauthamer, New York, N. Y.

Application August 19, 1947, Serial No. 769,408

2 Claims. (Cl. 240—78)

1

This invention relates to a drop-extension member for adjustably attaching a globe or similar light diffusing member to an electric lighting fixture and refers particularly to an extensible attaching and carrier member for lighting fixtures whereby a disk shaped globe, disk or plate shaped light diffuser may be lowered without removing same from the fixture to permit accessibility to light bulbs when necessary to replace same.

An object of this invention is the provision therein of an extensible carrier element in a light fixture which will hold suspended, a globe, disk or plate light diffuser thereon, and permit the said light diffuser to be lowered without detachment from said fixture thereby making the light bulbs readily accessible for replacement, and including a means for holding the said light diffusing element in its raised or lowered position.

Another object of this invention is the provision therein of an extensible carrier member which will support a canopy and permit the lowering of same without detachment from the lighting fixture thereby providing ready access to the wiring connections normally covered by the canopy.

A still further object of this invention is the provision of a device in which the constituent elements are so arranged structurally and functionally as to assure improved results with materials and members which may be manufactured at reasonable cost, may be easily assembled and which will be efficient in operation with minimum wear to the parts.

The invention possesses other objects and features of advantage, some of which, with the foregoing will be set forth in the following description and in the claims wherein parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

Figure 1 is a sectional view, in elevation, of one end of a light box, showing an extensible carrier member supporting a glass plate against the under side of a light fixture.

2

Figure 2 is a similar view showing the extensible carrier member extended and holding the glass plate in its lowered position and opening the light box.

5 Figure 3 is a perspective view of a complete lighting fixture as viewed in a recess in a ceiling.

Figure 4 is a similar view showing the light box open and the ceiling structure in section with the front wall of the light box removed.

10 Figure 5 is a sectional view of a lighting fixture showing a bowl shaped light diffuser supported by the extensible carrier member. The full lines showing the bowl in its normally raised position while the dot-dash lines show the extensible carrier member and its attached bowl in lowered position.

Figure 6 is an enlarged view, in detail, of the lower portion of the extensible carrier member.

20 Figure 7 is a pulled apart view of the various parts of the extensible carrier member forming the basis of this invention.

Figure 8 is a perspective view of a lighting unit mounted in a ceiling recess and shows two extensible carrier members.

25 Figure 9 is a longitudinal sectional view of one end of the fixture shown in Figure 11.

Figure 10 is a view similar to that of Figure 9 but shows the extensible plate carrier extended to lower the attached plate and thus open the light box of the fixture.

30 Figure 11 is a sectional elevational view showing another application of the extensible carrier member.

Referring in detail to the parts, 11 designates 35 a stem-like hanger having a threaded upper end portion 12 and a thickened lower end portion 13. The upper end 12 extends through an aperture in a light box 14 and is held thereon by means of the nuts 15 and 16. The light box 14 may be suitably held in a recess 17 in the ceiling structure 18. The expanded portion of the end 13 forms a shoulder or ledge 19 over and against which a cap 20 engages. The said cap 20 is threaded upon and attached to the upper threaded portion 21 of a tubular carrier member 22 engaging around the said stem-like hanger 11 and adapted to vertical reciprocal movement thereon. The lower end portion of the tubular carrier member 22 is threaded as at 23 and has threaded thereon a circular or nut member 24 and a cap 25 having an orifice 26 of sufficient diameter to allow the broadened end 13 of the stem-like hanger 11 to engage therethrough.

The narrower portion of the aforesaid stem 11 is adapted to engage through an orifice 27 in the cap 20. Interposed between the nut 24 and the cap 25 there is a plate member 28 of glass or any suitable translucent material and between the said plate 28 and the nut 24 and cap 25 there is 55 disposed washers 29 and 30 respectively, of any

suitable resilient material. A cap 31 having a nut formation 32 thereon is adapted to be threaded upon the lower threaded end 13 of the stem-like hanger 11 when the said stem-like hanger extends through the orifice 26 as shown in Figures 1, 3, 5, and 6.

The complete extensible carrier member comprises six parts, see Figure 6, which may be assembled in the following order. The cap 20 is slipped over the end 12 of the stem 11 and the said end 12 of the stem is secured to the light box 14 by means of the said nuts 15 and 16. The tubular carrier member 22 is then threaded into the cap 20, the washer-nut 24 then threaded over the threaded end 23, of the tubular carrier member 22. A resilient washer 29 follows and a glass plate 28, or any suitable light diffusing member, is slipped over the end 23 and held against the resilient washer 29 by means of the cap 25 threaded upon the extreme end 23 of the tubular carrier member 22; a washer 30 of suitable resilient material being interposed between the plate 28 and the cap 25. The device thus assembled will assume the appearance indicated in Figure 2 which shows the light diffusing plate 28 held in its lowered position away from the light box 14 exposing the light bulbs 33 and making them accessible for removal and replacement.

Figure 1 shows the stem-like hanger 11, of the extensible carrier member telescoped within the tubular carrier member 22 and the end 13 of the said stem protruding through the orifice 26 of the cap 25 to receive upon its extreme end a cap-nut 31 which is screwed thereon as already shown in Figure 6. In the position just described, the plate 28 is held closely against the light box (Figs. 1, 3 and 9). When, however, the cap-nut 31 is removed, the tubular member 22, carrying the plate 28 is allowed to drop until the shoulder 19 on the stem-like hanger 11, engages the cap 20 through the orifice 27 of which the said stem-like hanger 11 engages, as clearly shown in Figure 2.

In Figure 3, there is shown a ceiling fixture having a light box 14 recessed in the ceiling 18, and shows a light diffusing plate 28 of transparent or translucent material held in its closed position by the cap-nuts 31. When these cap-nuts are removed, the plate 28 will drop to the position shown in Figure 4, opening the light box 14 and exposing the light tubes 33.

In Figure 5, a regulation ceiling fixture is shown. In this type the stem 11 is attached to the cover plate 34 of an outlet box 35 suitably attached in a recess in the ceiling 18. Wires 36 and 37 leading from a conduit connection (not shown) in the said outlet box 35, supply current to the light bulbs 38 and 39 respectively and a bowl shaped globe 40, usually of translucent material masks the said light bulbs and is held in place, as shown, by the cap-nut 31 which in turn engages the orificed cap 25 to hold the tubular member 22 in its uppermost position as shown by the full lines. The dot-dash lines indicating the lowered position of the extensible carrier member and its attached globe 40.

Figure 8 shows a plate 28' suspended by a single extensible carrier member at each end thereof and a light box 14' recessed in the ceiling 18, the light bulbs 33' being one or more in number. Figure 9 shows the closed position of the light box 14' and extensible member carrying the plate 28'. Figures 9 and 10 show the closed and

open condition respectively, of the light fixture.

Figure 11 shows still another application of the extensible carrier member, wherein recessed ceiling light fixture, having a high intensity light bulb, is mounted in a ceiling recess or pocket 53. A plate 54 is suitably attached in said pocket and carries a socket 55 and light bulb 56 around which there is mounted a reflector 57 whose outer lower edge is formed with an annular flange 58. The stems 11 are three or more in number and are attached to the plate 54 in the manner already described. To the lower ends of the tubular members 22 there is attached, by means of nuts 59 and caps 25, an annular ring 60 which is formed with an annular ledge 61 adapted to carry a plate 62 of suitable translucent material. The full lines in this figure show the lowered or opened position of the lighting fixture while the dot-dash lines show raised position of the movable parts and the closed position of same.

I claim:

1. In a ceiling light fixture comprising an open end light box recessed within a ceiling structure, a light unit within the light box, a multiplicity of supporting members secured within the light box, the lower ends of the supporting members extending below the open edges of the light box, the supporting members comprising stem-like hangers having their upper ends secured to the light box, their lower ends broadened to form a shoulder and a threaded portion upon the broadened end, tubular carrier members externally threaded at both ends and slidably engaging over the stem-like hangers, orificed caps threaded upon the upper ends of the tubular carrier members, engaging over the stem-like hangers and contacting the shoulder formed thereon to limit the downward movement of the tubular carrier, a light diffusing plate having orifices therein engaging over the lower threaded ends of the tubular carriers, orificed internally threaded members engaging the lower threaded ends of the tubular carriers to hold the diffusing plate upon the tubular carriers and supporting nuts having a threaded bore engageable with the threaded broadened ends of the stem-like hangers adapted to hold the tubular carrier members and their attached light diffusing plate in raised position.

2. In a ceiling light fixture a set forth in claim 1, including internally threaded adjustable washers engageable upon the lower threaded portions of the tubular carrier members and orificed gaskets engaging over the lower threaded portions of the tubular carrier members disposed between the adjustable washers and the light diffusing plate and the supporting nut and light diffusing plate.

JOSEF KRAUTHAMER.
